UNITED STATES PATENT OFFICE.

THOMAS W. PRITCHARD, OF WILMINGTON, NORTH CAROLINA, ASSIGNOR TO NATIONAL WOOD DISTILLING COMPANY, OF WILMINGTON, NORTH CAROLINA, A CORPORATION OF NORTH CAROLINA.

PROCESS OF TREATING CREOSOTE-OIL.

1,185,592.

Specification of Letters Patent.

Patented May 30, 1916.

No Drawing. Application filed August 14, 1911, Serial No. 643,909. Renewed October 26, 1915. Serial No. 58,068.

To all whom it may concern:

Be it known that I, THOMAS W. PRITCHARD, a citizen of the United States, residing at Wilmington, in the county of New Hanover, State of North Carolina, have invented 5 certain new and useful Improvements in Processes of Treating Creosote-Oil, of which the following is a description.

My invention relates to the treatment of 10 creosote oil produced by the destructive distillation of resinous wood, and consists in the herein described process of producing from such creosote oil an oil having the characteristics of rosin oil, and in the oil so 15 produced.

In carrying out the process of my invention I take ordinary commercial heavy wood creosote oil produced by destructive distillation of pine or other resinous wood, which is 20 characterized by a dark brown color and strong creosote or tarry odor, and first subject it to a heat not substantially in excess of 500 degrees F. in a still, which may be of any desired form, provided only that it is 25 heated evenly throughout, and it can be brought to and maintained as long as necessary at the degree of heat desired. I prefer to use a still heated by circulation of a fluid, as described in the U. S. patent issued to me 30 February 25, 1908, No. 880,466. By heating the still to not substantially exceeding 500 degrees F. and maintaining the heat for a short time a light oil is driven off, having substantially the same odor as the heavy 35 creosote oil, but light brown in color and very fluid. This I term light creosote oil. After this light creosote oil has been completely driven off by continuing the heat at about 500 degrees until vaporization ceases, 40 I increase the heat. At about 550 degrees F. a heavy oil begins to distil off. This heavy oil is a clear viscous oil, wholly free from creosote or tarry odor and practically free from any odor whatever, though having a slight phenol odor, and has the general characteristics of a high grade rosin oil, but 45 having a less content of rosin acids and

lower iodin value than rosin oil and having a higher content of oxidized acids. The heat may be gradually raised to 650 degrees 50 F., or even 700 degrees F., and the heavy oil continues to distil over the oil distilled at temperatures above 550 degrees F., being lighter in color than that distilled at 550 F., being about the same as regards viscosity 55 and freedom from odor, whatever the heat, between 550 degrees F. and 700 degrees F., employed. I prefer not to carry the heat above 700 degrees F., as a higher heat might cause the residue in the still to crack and be 60 broken up into substances which might not be useful or desirable. After the still has been maintained at the highest heat found desirable until the heavy oil ceases to be distilled off, it is cooled, and the residue consisting of pitch-like material is removed and 65 mixed with the light creosote oil first distilled off, producing an oil closely resembling the heavy creosote oil first introduced into 70 the still.

It will of course be understood that in heating up the still at the beginning of the operation that light creosote oil will begin to be distilled off at a comparatively low temperature, and if desired the oil distilled 75 at different temperatures may be kept separate. So also in distilling off the heavy oil at 550 degrees F. and higher, the oil distilled at different temperatures may be kept 80 separate.

It will of course be understood that the temperatures herein given are approximate only, and may be varied somewhat without departing from the spirit of the invention.

Having thus described my invention, what 85 I claim and desire to secure by Letters Patent is:

1. The process of treating wood creosote oil produced from resinous wood and having the characteristic creosote odor, to produce an oil free from creosote odor, which consists in heating the creosote oil to a temperature not exceeding 500 degrees F. and maintaining it at such temperature until all 90

substances having creosote odor have been distilled off and then raising the temperature to not exceeding 700 degrees F. and distilling off oil free from creosote odor.

5. 2. The herein described oil produced from creosote oil by the herein described process having the general characteristics of resin oil but having a less content of rosin acids

and lower iodin value than rosin oil and having a higher content of oxidized acids. 10
This specification signed and witnessed

this 8th day of August.

THOMAS W. PRITCHARD.
